COLLECTOR'S STAMP

George J. Matt, Brooklyn, N. Y., assignor to Roberts Numbering Machine Company, New York, N. Y., a corporation of New York

Application April 21, 1934, Serial No. 721,700

14 Claims. (Cl. 101—90)

The invention relates to collector's stamp, and more particularly to a portable, manually operative machine for making, simultaneously, a plurality of records of each transaction in which 5 the machine is used.

In the use of a collector's machine embodying the invention, in order to protect the payer of funds to a collector and the principal for whom such collections are made, a record is made indicating the payer, the amount paid and other 10 data upon the book of the payer and upon a record strip so protected within the machine as not to be accessible to the collector, thus avoiding all 15 possibility of any alterations in the entries upon this record and ensuring a complete temporary record of all transactions which may be entered in a permanent record book.

It is not only essential that the various mechanisms be so constructed and arranged as to permit 20 the convenient setting of the various indicia wheels by the collector to indicate different transactions, but the various parts must be so constructed as to permit such compactness throughout the machine as to make it conveniently portable and preclude all possibility of a disarrangement 25 of parts or an improper setting of the various indicia wheels.

Each of the indicia wheels is so formed as to indicate clearly to the collector what data will 30 be impressed by the machine with the actuation thereof, thus preventing any mistake in the record made by the machine.

Each indicia wheel must be freely rotatable to facilitate the setting of the various wheels required 35 in making an entry, and yet each wheel must be under such control as to prevent its accidental displacement after it has once been set, thus avoiding the making of an imperfect record because of the accidental rotation or partial rotation of any wheel being used in making that record.

In a machine of the type to which the invention relates, the use of ink pads or ink saturated strips of fabric is not satisfactory since such devices 45 cannot be relied upon to make a sharply defined record with the actuation of the machine and are inclined to smut the record strip, and the purchaser's record as well, unless the latter is carefully handled when positioning it in relation to the printing mechanism.

A machine embodying the invention is provided with means by which after each actuation thereof, the record strip and the strips associated therewith, through which data are impressed 55 thereon and on the payer's record book, is auto-

matically advanced so as to properly space succeeding entries and ensure a clear sharp impression of the data as determined by the manual setting of the various indicia wheels.

The construction is such as to permit the use of strips of carbon paper with an interposed record strip which latter serves as a reinforcement to the former, thus precluding all possibility of the tearing of the carbon strips and the failure to impress thereon, or upon the payer's record, the 10 desired data.

Certainty of the making of an impression with each actuation of the machine is essential and it is also desirable to provide in the machine, means preventing its accidental actuation in a 15 manner to impress data upon the record strip without impressing corresponding data upon the payer's record book.

The manner of mounting the record strip and the strips associated therewith through which the impression is made, is such that the movement of the indicia wheels, while engaged therewith, will create sufficient slack prior to the making of the impression to avoid mutilation of said strips or smutting of the imprint, the strip feeding mechanism being actuated during radial movement of said wheels following the making of the impression, means preferably being provided to prevent the possible creation of slack during such feeding movement.

The invention consists primarily in a collector's stamp embodying therein a lower casing having an opening through the bottom thereof, supply and rewind reels upon opposite sides of said opening, a plurality of superimposed strips of record and carbon paper passing from said supply to said rewind reel with a carbon coated surface presented towards said opening, guides for said strips, an upper casing having a sight opening therethrough, closing said lower casing, 40 movable therefrom, and having therein a guide bracket having vertical ways, a reciprocatory frame, a shaft carried thereby having its opposite ends mounted in said ways, and a plurality of wheels idly mounted on said shaft, and projecting through said sight opening, each having a plurality of duplicated printing and non-printing characters so positioned that when a printing character is at the opening in the lower casing, the duplicate non-printing character is at said sight opening, means whereby said frame may

be actuated, and cooperating means carried by said rewind reel and said reciprocatory frame whereby said strips will be advanced with each upward movement of said frame; and in such 50 55

other novel features of construction and combination of parts as are hereinafter set forth and described, and more particularly pointed out in the claims hereto appended.

5 Referring to the drawing.

Fig. 1 is a front elevation of a machine embodying the invention, partly in section;

Fig. 2 is a section on the line 2—2 of Fig. 1;

10 Fig. 3 is a top plan view of the lower casing, showing the manner of mounting the record and associated strips, said strips being broken away to disclose structural details of the base;

Fig. 4 is a section on the line 4—4 of Fig. 1; and

15 Fig. 5 is a bottom plan view of the upper frame.

Like numerals refer to like parts throughout the several views.

In the embodiment of the invention shown in 20 the drawing, the machine contains therein an angular cupped lower casing 10 having an opening 11 through the bottom thereof. Within this casing are side bars 12, each having saddles 13 and 14 upon opposite sides of the opening 11 25 forming lower bearings for a supply reel 15 of superimposed strips 16, 17 and 18 of record paper and carbon paper, and a rewind reel 19 by means of which each strip is fed across said opening 11 following each actuation of the machine. The side bars 12 are connected by rods 20 above the opening 11, which serve as guides for the passage of the strips 16, 17 and 18. The lower casing 10 is supported from a base plate 21 by means of a side bar 22 and screws passing therethrough and through one of the side bars 12 as shown in Fig. 3 of the drawing.

The base 21 adjacent the bar 22 is of greater thickness than other portions of the base, so as to space the casing 10 away from said base 40 to an extent to permit the insertion of the leaves of a debtor's record book between said casing and said base. This space is indicated at 23 in Figs. 1, 2 and 4. Loosely mounted in the base 21 are a plurality of presser plungers 24, so 45 that after the insertion of the book in the space 23, it is merely necessary to set the machine upon some object, to hold said book against displacement during the actuation of the machine. These plungers are positioned upon opposite sides of the opening 11 so as to press the book against the bottom of the casing 10. Insert in the base 21 along the longitudinal center of the opening 11 is a soft platen 25 to ensure the making of a clean impression with the actuation of the machine upon the record book and also upon the record sheet. This platen is desirable, although not necessary.

A stamp embodying the invention is equipped or loaded with a record strip and its associating carbon strips before it is delivered to the collector. It is desirable that this strip be inaccessible to the collector since it is a check upon his activities and determines the amount of cash which must be turned in after each day's 55 work. The lower casing, however, must be readily accessible to those authorized to have access to said record strip, to facilitate the removal of a used record strip and the charging of the machine with a fresh strip.

70 To prevent access to the record strip by a collector, while permitting the free changing in the setting of the machine, I provide a top casing 26, which not only closes the lower casing 10, but supports various mechanisms for 75 making an impression and ensuring the feeding

of the record strip following each actuation of the machine.

This casing has a sight opening 27 in the front wall thereof and carries a U-shaped bracket 28 having guideways 29 in the legs thereof, which guideways, when the machine is closed, register with recessed portions 30 in the bars 12. The base of the bracket 28 is extended lengthwise of the machine so as to support the upper casing 26 from the side bars 12. This extended portion of each side of the U-bracket is provided with saddles 31 registering with the saddles 13 and 14 of the side bars 12 respectively, thus completing the bearings for the reels 15 and 19.

15 Carried by the bracket 28 is a spring 32 acting as a friction retard device operative upon the supply reel 15 to prevent the creation of slack in the strips 16, 17 and 18 with the actuation of the take-up mechanism in a manner to be 20 hereinafter described.

The bracket 28 also has hinge members 33 adapted to be pivoted to the projecting ends of the side bars 12 to permit the top casing to be removed from its position in closing the lower casing 10, to permit the mounting and removal of the reels and the record strips from 25 said lower casing.

Slidably mounted in relation to the U-bracket 30 28 is a U-frame 34 carrying a shaft 35, the opposite ends of which project beyond said U-frame and enter the guideways 29 in the bracket 28, thus permitting said U-frame to have a controlled vertical reciprocatory movement in the 35 operation of the stem. This frame like the bracket 28 is within the top casing 26.

The shaft 35 has idly mounted thereon, a plurality of indicia wheels, having a sequence of printing characters projecting from the perimeter thereof. The number of these characters and their nature vary according to the data which are to be recorded by means of the various wheels. The general character of these wheels is similar to those used upon an ordinary numbering head, but different therefrom in that the succeeding printing characters are spaced apart sufficiently to permit the locating between succeeding characters, of duplicated characters to indicate the setting of the various wheels of the machine. There is, therefore, upon each wheel, a pre-determined number of printing characters and a duplication of these characters in a non-printing position upon the wheel. In the wheel as shown in the drawings, there are 12 printing characters and 12 non-printing characters. Each pair of duplicated characters is so positioned that when a printing character is brought to its printing position above the platen 25, the other of said pair is positioned at the sight opening 27. With this arrangement, the operator may turn the several wheels by hand to set up the desired data and may read through the sight opening what the setting of the various wheels is. These wheels may be so set as to 50 indicate the date, the number of the account, the amount collected, the key letters of the collector and any other data which may be desired in order to identify each record strip after its removal from the machine with the work of a particular collector and with the various debtors from whom collections have been made.

55 In the accompanying drawing, the various digit wheels are indicated at 36, the printing characters thereon at 37 and the non-printing characters at 38. The printing characters are 75

in cameo or typo, while the non-printing characters are in intaglio permitting the lines thereof to be filled with suitable coloring matter in order to permit the setting of the machine to be readily ascertained.

Each indicia wheel has connected thereto, a ratchet wheel 39, the teeth of which correspond in number with the number of printing characters upon the wheel. With twelve printing characters, as shown in the drawing, the ratchet wheel 39 will have twelve teeth. These ratchet wheels also aid in securing a proper spacing of the printed characters in each impression.

Co-operating with each ratchet wheel 39 is a 15 detent pawl 40 acted upon by one tooth of a comb spring 41, which is mounted upon the reciprocating frame 34 by means of the rod 42 passing from leg to leg of said frame. There is one more tooth on this comb spring than there are detent 20 pawls, this tooth being utilized for controlling the actuation of the take-up mechanism operative upon the rewind reel.

As shown in the drawing, the comb spring 41 is provided with a looped portion 43 seated between the rod 42 and the ends of the various detent pawls, one edge of this spring being curved as shown at 44 in Fig. 4 so as to partially encircle said rod 42 in a manner to prevent displacement of the comb spring under ordinary conditions of use of the machine. The various detent pawls as well as the actuating member for the take-up mechanism are pivoted upon the rod 45.

It will be noted that with the above construction, each time an indicia wheel is turned, the 35 detent pawl limits the step by step movement of the wheel to a movement in arc corresponding with the space occupied by one printing and one non-printing character.

It will be noted that the detent pawls and the 40 springs operative thereon have movement with the indicia wheels, so that each of these wheels is restrained at all times excepting during the manual setting of the wheel, in a manner to prevent such accidental turning of a wheel through 45 one step or a part thereof, with a resultant recording of improper data or loss of register of the various wheels to an extent to occasion any confusion in the printed record either upon the debtor's book or upon the record strip.

The reciprocating frame 34 is supported in relation to the top casing 26, and the U-bracket 28 connected therewith, by means of a stem 46 passing through openings in the bracket 28 and in the top casing 26 and the spring 47 acting between 55 the top of said casing and the enlarged head 48 of said stem. Telescoping sheathings 49 and 50 are used to enclose said spring to an extent to prevent possible blocking or displacement thereof.

The stem has two spaced ratchet teeth 51 and 60 52 therein adapted to be engaged by a sliding latch plate 53 seated between the top of the bracket 28 and the top of the casing 26, space being provided for the movement of this plate by means of the spacing screws 54 by means of 65 which the bracket 28 is attached to the casing 26. A spring 55 acts upon the plate 53 with a tendency to engage it with the ratchet teeth 51 or 52 according to the position of the stem 46.

As heretofore stated, means must be provided 70 to advance the record strip and its associated carbon strips following the making of each impression upon the former. I employ for this purpose, a take-up mechanism consisting of a ratchet wheel 56 carried by and rotatable with the 75 rewind reel 19. Mounted in the lower casing 10

adjacent said wheel is a spring pressed detent pawl 57 for offering sufficient resistance to the movement of the ratchet 56 with which it co-operates to avoid in conjunction with the brake member 32, movement of said strips to create sufficient slack therein adjacent the opening 11 as might result in the smutting of the imprint. Pivoted upon the rod 45 is a rocking pawl 58 having an arm 59 engaged by one of the teeth of the comb spring 41. The pawl 58 is disengaged from the ratchet wheel excepting towards the limit of the downward movement of the frame 34. With the upward movement of said frame by the spring 47, said pawl engages and imparts turning movement to the ratchet wheel 56 and rewind reel 19, to take up any slack created in the strips 16, 17 and 18 prior to the making of an impression and to advance the record strip 17. The detent pawl 57 is mounted upon one of the side bars 12.

The casings 10 and 26, while the machine is in use by a collector, may be locked together to prevent access to the record strip. In the drawing, an ordinary snap lock is shown, but any other desired form of lock may be employed.

The part shown at 60 is a mere stop member limiting the movement of the pawl 58 to an extent to maintain it in a position in relation to the ratchet wheel 56 to avoid possibility of reverse movement of the rewind reel 19 with the downward movement of the pawl. The detent pawl 57 will also prevent such reverse movement of the 30 rewind reel in the manner above described.

The record and its associated carbon strips, by their arrangement and their relation to each other and to the various parts of the mechanism, permit the making of the impression upon a debtor's record book and the record strip without fouling the printing characters upon the various indicia wheels 36 so as to permit the hand turning of these wheels without soiling the hands of the user of the machine. The strip 18 is a carbon paper strip, the coated surface of which is presented toward the opening 11, the strip 17 is superimposed upon the strip 18 and is a record strip of lightweight, tough paper, while the strip 16 is a carbon paper strip with its coated surface engaging the strip 17. By this arrangement, the record impressed upon the strip 17 by means of the strip 16 is identical with the record impressed upon the debtor's book by means of the strip 16. The strip 17 possesses sufficient inherent strength to preclude possibility of the tearing of either carbon strip.

The spindles of the reels 15 and 19 may take any desired form, the spindle 19, in the form of the invention shown, being tubular with diametrically opposite slots to facilitate the connection of an end of a composite strip 16, 17 and 18 thereto. Either or both spindles may be flanged or not, as desired, although the rewind spindle ordinarily is provided with flanges 61 spaced from each end thereof to provide the end arbors co-operating with the saddle 14 of the side bars 12 of the lower casing. The ratchet wheel 56 is in engaging relation with one of the flanges 61, and this flange prevents possibility of skewing of the strips in a manner to cause their mutilation by, or interference in the operation of, the pawl 58.

The manner of use of the herein described stamp, and its mode of operation is substantially as follows:—

A collector is furnished with a list of debtors and the amount to be collected from each with 75

the key number of the account. The principal, before delivering a machine to the collector, turns the upper casing 26 upon its hinges and mounts a supply reel 15 in the bearings 13. The ends of the strips 16, 17 and 18 are then drawn from the supply reel and passed under the guide and spacer rods 20 and connected to the rewind reel 19. The latter is then mounted in the bearing saddles 14 and the top casing is closed upon, and locked in relation to, the lower casing 10.

15 The plate 53 is normally engaged by the spring 55 with one of the notches 51 or 52, thus preventing accidental movement of the stem 46 and the reciprocatory frame 34 carrying said stem.

16 When making a collection, the collector turns the necessary number of indicia wheels 36 to set up the desired printing characters 37 to indicate the necessary data in connection with that collection. As stated, this data may include various items such as the date, the amount, the identification of the account and identification of the collector. In turning the wheels, there is no possibility of soiling the hand and no fouling of the printing characters by fibrous matter can 20 result from continued use of the machine. In fact, the wheels always remain dry and clean.

25 In setting up the desired printing characters, the collector is guided entirely by the non-printing surfaces 38. These surfaces, in the form of the invention shown in the drawing, are positioned about 120° from the printing line so as to be readily visible through the opening 27, which opening must be sufficiently large to permit access to the wheels without difficulty and to allow 30 for the reciprocatory movement of the wheels.

35 The various detent pawls 40 offer sufficient resistance to the turning of the wheels to permit accuracy in the setting thereof, and to prevent accidental turning of any wheel after it has once been set. This setting is by a step by step movement, the number of teeth on the ratchet wheels 39 being such as to ensure a 30° movement with each step, in the form of the invention shown. This precludes possibility of error in the positioning of the printing characters, or the accidental positioning of a non-printing or setting character where a printing character should be. The positioning of the non-printing characters upon surfaces recessed in relation to the printing characters, affords gripping areas within the 40 plane of the printing surfaces which may be utilized in turning the wheels.

45 In closing the top casing upon the lower casing, the brake member 32 will be engaged with the spindle of the supply reel 15 in a manner to develop resistance to the turning movement of this spindle.

50 The stamp now being properly set, the collector inserts the debtor's record book in the slot or space 23, the thickened portion of the base 21 locating the blank spaces upon the sheets of this book in a proper relation to the printing wheels, side gauge markings being used to indicate the line of the book upon which the data is to be 55 impressed. One difficulty encountered in the use of a stamp embodying the invention is that the thickness of the record book varies with different books, or with the same book at different times. Consequently, the space of slot 23 must be sufficiently deep or wide to accommodate the maximum thickness of such a book.

56 The clamp pins 24 are provided to hold a book in any adjusted position while an impression is being made. By setting the stamp upon any flat 60 object, this holding means is made operative.

When an impression is to be made, the collector presses the latch plate 53 inwardly against the tension of the spring 55 and strikes the enlarged head 48 of the stem 46 a sharp blow, thus forcing the reciprocatory frame 34 downwardly toward the platen 25. Toward the end of this downward movement, the printing characters engage the uppermost carbon strip 16 forcing this strip, the record strip 17 and the lower carbon strip 18 downwardly until the strip 18 engages the record book positioned within the slot 23. Toward the end of this downward movement, the pawl 58 engages the teeth of the ratchet wheel 56 and rides thereover, the spring operative upon this pawl permitting it to yield freely in passing 15 the ratchet, and the detent pawl 57 offering sufficient resistance to the turning movement of said ratchet to prevent the creation of slack adjacent the rewind reel 19. Slack will be created, however, in the said strips because of the necessity of forcing said strips downwardly through the opening 11 so as to engage the record book. This slack will vary slightly, according to the thickness of the book, but will never be material. It results from the turning movement of 20 the supply reel which, as stated, is resisted by the spring 32.

25 The downward movement of the frame 34 is against the tension of the spring 47.

30 After making the impression, the collector again presses the lock plate 53, in case he has relieved the pressure upon this plate following the striking of the head 48, thus permitting the spring to raise the frame 34 and the actuating pawl 58 for the rewind reel, during which movement the slack created in the strips 16, 17 and 18 will be taken up and a length of said strips advanced in relation to the printing line and wound upon the 35 rewind reel preparatory to the making of the next impression. The spacing of the data recorded upon the record strip 17 will vary with the increase in the diameter of the rewind reel, but the amount of this variance will be negligible.

40 The cameo or typo characters will engage the paper backing for the carbon strip 16, so that 45 there are no fibers or coloring matter accumulated upon these characters.

45 Upon the limit of the upward movement of the stem 46, the latch plate 53 becomes automatically operative to prevent movement of the stem, and remains in this position, precluding possibility of the accidental depression of the frame 34. The only effect of such accidental movement would be to soil the platen 25 and unnecessarily advance the record strip.

50 It is obvious that instead of using three strips 16, 17 and 18, the record strip may be a carbon strip with a paper backing of sufficient weight to impart the desired strength to the composite 55 printing strip.

56 The number and arrangement of parts is such as to ensure a minimum of simple mechanisms, the actuation of which is such as to minimize likelihood of error in the setting of the various 60 wheels and preclude likelihood of the disarrangement or breakage of parts.

65 It is essential, in a stamp of the type to which the invention relates, that it shall not get out of order since if the stamp does not function properly, there is a failure to properly record all of the 70 transactions in which the stamp is used.

75 The stamp of the invention is not primarily to prevent the stealing of collected funds, but to ensure the application of funds collected to the proper accounts. Experience has demonstrated 75

that shortages in the accounts of collectors are cumulative and arise most frequently because of the extension of favors to debtors by the collector. This is done by applying to one account, advance

5 payments made on another account. In other words, in installment collections or in industrial insurance collections, many of the debtors prefer to pay a number of installments or premiums at one time to avoid the annoyance of frequent 10 payments. Other debtors find themselves unable to meet payments when due. The collectors, in order to carry the non-paying debtors, may at times apply part of a payment by one debtor to the account of another debtor, relying upon the 15 latter to make good the shortage within a reasonable time. If this is not done, there is confusion in the accounts and upon investigation the shortage is detected.

The stamp herein described, by making a record as to each payment made the collector and the account to which the collection is to be credited, prevents this practice, since the failure of any debtor to make a payment upon a due date is evidenced by the absence of data in the printed record upon the record strip of the stamp. The correct amount of each payment must be made upon the debtor's record book and the corresponding entry must be made upon the record strip. Collusion between the debtor and the collector is out 30 of the question. Consequently, the use of a stamp embodying the invention has the three-fold advantage of enabling a principal to credit each collection to the proper account, to act as a check upon the cash returns of the collector and to accurately determine what installments or premiums are not collected when due.

The use of indicia wheels idly mounted upon a shaft carried by a reciprocatory frame having a right line movement toward and from the surfaces upon which matter is to be impressed, and the exposure of a portion of the perimeter of these wheels through a sight opening in the top casing, not only increases the range of the variation of the records which may be impressed, but permits 45 the use of wheels of small diameter and avoids necessity for additional mechanisms for turning the wheels or indicating the setting thereof.

It is not my intention to limit the invention to the precise details of construction shown in the 50 accompanying drawing, it being apparent that such may be varied without departing from the spirit and scope of the invention.

Having described the invention, what I claim as new and desire to have protected by Letters 55 Patent, is:—

1. A collector's stamp embodying therein a lower casing having an opening through the bottom thereof, supply and rewind reels upon opposite sides of said opening, a plurality of superimposed strips of record and carbon paper passing from said supply to said rewind reel with a carbon coated surface presented towards said opening, guides for said strips, an upper casing having a sight opening therethrough, closing said lower casing, movable therefrom, and having therein a guide bracket having vertical ways, a reciprocatory frame, a shaft carried thereby having its opposite ends mounted in said ways, and a plurality of wheels idly mounted on said shaft, and projecting through said sight opening, each having a plurality of duplicated printing and non-printing characters so positioned that when a printing character is at the opening in the lower casing, the duplicate non-printing character is at said sight opening, means whereby said frame

may be actuated, and co-operating means carried by said rewind reel and said reciprocatory frame whereby said strips will be advanced with each upward movement of said frame.

2. A collector's stamp embodying therein a lower casing having an opening through the bottom thereof, and side bars having bearing saddles adjacent the opposite ends thereof, supply and rewind reels removably mounted in said saddles, a plurality of superimposed strips of record and carbon paper passing from said supply to said rewind reel with a carbon coated surface presented towards said opening, guides for said strips, an upper casing having a sight opening therethrough, closing said lower casing, movable therefrom, and having therein a guide bracket having vertical ways having extensions provided with bearing saddles co-operating with the saddles in said side bars, a reciprocatory frame, a shaft carried thereby having its opposite ends mounted in said ways, and a plurality of wheels idly mounted on said shaft, and projecting through said sight opening, each having a plurality of duplicated printing and non-printing characters so positioned that when a printing character is at the opening in the lower casing, the duplicate non-printing character is at said sight opening, means whereby said frame may be actuated, and co-operating means carried by said rewind reel and said reciprocatory frame whereby said strips will be advanced with each upward movement of said frame.

3. A collector's stamp embodying therein a platen base, a lower casing having an opening through the bottom thereof supported by and spaced from said base, supply and rewind reels upon opposite sides of said opening, a plurality of superimposed strips of record and carbon paper passing from said supply to said rewind reel with a carbon coated surface presented towards said opening, guides for said strips, an upper casing having a sight opening therethrough, closing said lower casing, movable therefrom, and having therein a guide bracket having vertical ways, a reciprocatory frame, a shaft carried thereby having its opposite ends mounted in said ways, and a plurality of wheels idly mounted on said shaft, and projecting through said sight opening, each having a plurality of duplicated printing and non-printing characters so positioned that when a printing character is at the opening in the lower casing, the duplicate non-printing character is at said sight opening, means whereby said frame may be actuated, and co-operating means carried by said rewind reel and said reciprocatory frame whereby said strips will be advanced with each upward movement of said frame.

4. A collector's stamp embodying therein a platen base, a lower casing having an opening through the bottom thereof supported by and spaced from said base, plungers movably mounted in and projecting from the bottom of said base, supply and rewind reels upon opposite sides of said opening, a plurality of superimposed strips of record and carbon paper passing from said supply to said rewind reel with a carbon coated surface presented towards said opening, guides for said strips, an upper casing having a sight opening therethrough, closing said lower casing, movable therefrom, and having therein a guide bracket having vertical ways, a reciprocatory frame, a shaft carried thereby having its opposite ends mounted in said ways, and a plurality of wheels idly mounted on said shaft, and pro-

jecting through said sight opening, each having a plurality of duplicated printing and non-printing characters so positioned that when a printing character is at the opening in the lower casing, the duplicate non-printing character is at said sight opening, means whereby said frame may be actuated, and co-operating means carried by said rewind reel and said reciprocatory frame whereby said strips will be advanced with each upward movement of said frame.

5 5. A collector's stamp embodying therein a lower casing having an opening through the bottom thereof, supply and rewind reels upon opposite sides of said opening, a plurality of superimposed strips of record and carbon paper passing from said supply to said rewind reel with a carbon coated surface presented towards said opening, guides for said strips, an upper casing having a sight opening therethrough, closing said lower casing, movable therefrom, and having therein a guide bracket having vertical ways, a reciprocatory frame, a shaft carried thereby having its opposite ends mounted in said ways, and a plurality of wheels idly mounted on said shaft, and projecting through said sight opening, each having a plurality of duplicated printing and non-printing characters so positioned that when a printing character is at the opening in the lower casing, the duplicate non-printing character is at said sight opening, means whereby said frame may be actuated, automatically acting locking means preventing accidental movement of the frame, and co-operating means carried by said rewind reel and said reciprocatory frame whereby said strips will be advanced with each upward movement of said frame.

6 6. A collector's stamp embodying therein a lower casing having an opening through the bottom thereof, supply and rewind reels upon opposite sides of said opening, a plurality of superimposed strips of record and carbon paper passing from said supply to said rewind reel with a carbon coated surface presented towards said opening, guides for said strips, an upper casing having a sight opening therethrough, closing said lower casing, movable therefrom, and having therein a guide bracket having vertical ways, a reciprocatory frame, a shaft carried thereby having its opposite ends mounted in said ways, and a plurality of wheels idly mounted on said shaft, and projecting through said sight opening, each having a plurality of duplicated printing and non-printing characters so positioned that when a printing character is at the opening in the lower casing, the duplicate non-printing character is at said sight opening, a stem having an enlarged head carried by said frame and exposed exteriorly of said top casing, a spring acting between said stem and said top casing in raising said frame, automatically acting locking means for preventing accidental movement of said frame, and co-operating means carried by said rewind reel and said reciprocatory frame whereby said strips will be advanced with each upward movement of said frame.

7 7. A collector's stamp embodying therein a lower casing having an opening through the bottom thereof, supply and rewind reels upon opposite sides of said opening, a plurality of superimposed strips of record and carbon paper passing from said supply to said rewind reel with a carbon coated surface presented towards said opening, guides for said strips, an upper casing having a sight opening therethrough, closing said lower casing, moveable therefrom, and having therein a guide bracket having vertical ways, a reciprocatory frame, a shaft carried thereby having

its opposite ends mounted in said ways and a plurality of wheels idly mounted on said shaft, and projecting through said sight opening, each having a plurality of duplicated printing and non-printing characters so positioned that when a printing character is at the opening in the lower casing, the duplicate non-printing character is at said sight opening, a stem having an enlarged head carried by said frame and exposed exteriorly of said top casing, a spring acting between said stem and said top casing in raising said frame, automatically acting locking means for preventing accidental movement of said frame, and co-operating means carried by said rewind reel and said reciprocatory frame whereby said strips will be advanced with each upward movement of said frame.

8 8. A collector's stamp embodying therein a lower casing having an opening through the bottom thereof, supply and rewind reels upon opposite sides of said opening, a plurality of superimposed strips of record and carbon paper passing from said supply to said rewind reel with a carbon coated surface presented towards said opening, guides for said strips, an upper casing having a sight opening therethrough, closing said lower casing, movable therefrom, and having therein a guide bracket having vertical ways, a reciprocatory frame, a shaft carried thereby having its opposite ends mounted in said ways, and a plurality of wheels idly mounted on said shaft, and projecting through said sight opening, each having a plurality of duplicated printing and non-printing characters so positioned that when a printing character is at the opening in the lower casing, the duplicate non-printing character is at said sight opening, means whereby said frame may be actuated, a ratchet wheel carried by said rewind reel, and a spring pressed pawl pivotally mounted upon, and movable with, said frame, said pawl being normally disengaged from said ratchet wheel, but engageable therewith upon the depression of said frame, whereby said rewind reel will be actuated with the upward movement of said frame.

9 9. A collector's stamp embodying therein a platen base, a lower casing having an opening through the bottom thereof supported by and spaced from said base, supply and rewind reels upon opposite sides of said opening, a plurality of superimposed strips of record and carbon paper passing from said supply to said rewind reel with a carbon coated surface presented towards said opening, guides for said strips, an upper casing having a sight opening therethrough, closing said lower casing, movable therefrom, and having therein a guide bracket having vertical ways, a reciprocatory frame, a shaft carried thereby having its opposite ends mounted in said ways, and a plurality of wheels idly mounted on said shaft, and projecting through said sight opening, each having a plurality of duplicated printing and non-printing characters so positioned that when a printing character is at the opening in the lower casing, the duplicate non-printing character is at said sight opening, a stem having an enlarged head carried by said frame and exposed exteriorly of said top casing, a spring acting between said stem and said top casing in raising said frame, a ratchet wheel carried by said rewind reel, and a spring pressed pawl pivotally mounted upon, and movable with, said frame, said pawl being normally disengaged from said ratchet wheel, but engageable therewith upon the depression of said frame, whereby said rewind

reel will be actuated with the upward movement of said frame.

10. A collector's stamp embodying therein a lower casing having an opening through the bottom thereof, supply and rewind reels upon opposite sides of said opening, a retard device operative upon said supply reel, a plurality of superimposed strips of record and carbon paper passing from said supply to said rewind reel with

10 a carbon coated surface presented towards said opening, guides for said strips, an upper casing having a sight opening therethrough, closing said lower casing, movable therefrom, and having therein a guide bracket having vertical ways,

15 a reciprocatory frame, a shaft carried thereby having its opposite ends mounted in said ways, and a plurality of wheels idly mounted on said shaft, and projecting through said sight opening, each having a plurality of duplicated printing

20 and non-printing characters so positioned that when a printing character is at the opening in the lower casing, the duplicate non-printing character is at said sight opening, means whereby said frame may be actuated, and co-operating means

25 carried by said rewind reel and said reciprocatory frame whereby said strips will be advanced with each upward movement of said frame.

11. A collector's stamp embodying therein a lower casing having an opening through the bottom thereof, and side bars having bearing

30 saddles adjacent the opposite ends thereof, supply and rewind reels removably mounted in said saddles, a plurality of superimposed strips of record and carbon paper passing from said supply

35 to said rewind reel with a carbon coated surface presented towards said opening, guides for said strips, an upper casing having a sight opening therethrough, closing said lower casing, movable

therefrom, and having therein a guide bracket having vertical ways having extensions provided

40 with bearing saddles co-operating with the saddles in said side bars, a spring carried by said upper casing and engageable with said supply reel, a reciprocatory frame, a shaft carried thereby

45 having its opposite ends mounted in said ways, and a plurality of wheels idly mounted on said shaft, and projecting through said sight opening, each having a plurality of duplicated printing and non-printing characters so positioned that when

50 a printing character is at the opening in the lower casing, the duplicate non-printing character is at said sight opening, means whereby said frame may be actuated, and co-operating means

55 carried by said rewind reel and said reciprocatory frame whereby said strips will be advanced with each upward movement of said frame.

12. A collector's stamp embodying therein a lower casing having an opening through the bottom thereof, supply and rewind reels upon opposite sides of said opening, a plurality of superimposed strips of record and carbon paper passing

60 from said supply to said rewind reel with a carbon coated surface presented towards said opening, guides for said strips, an upper casing having a sight opening therethrough, hingedly connected with said lower casing at one side of

65 the opening through the bottom thereof, and having therein a guide bracket having vertical ways, a reciprocatory frame, a shaft carried thereby having its opposite ends mounted in said ways, and a plurality of wheels idly mounted on said shaft, and projecting through said sight opening, each having a plurality of duplicated

70 opening, each having a plurality of duplicated

printing and non-printing characters so positioned that when a printing character is at the opening in the lower casing, the duplicate non-printing character is at said sight opening, means whereby said frame may be actuated, and co-operating means carried by said rewind reel and said reciprocatory frame whereby said strips will be advanced with each upward movement of said frame.

13. A collector's stamp embodying therein a lower casing having an opening through the bottom thereof, supply and rewind reels upon opposite sides of said opening, a plurality of superimposed strips of record and carbon paper passing from said supply to said rewind reel with

15 a carbon coated surface presented towards said opening, guides for said strips, an upper casing having a sight opening therethrough, closing said lower casing, movable therefrom, and having therein a guide bracket having vertical ways, a

20 reciprocatory frame, a shaft carried thereby having its opposite ends mounted in said ways, and a plurality of wheels idly mounted on said shaft, and projecting through said sight opening, each having a plurality of duplicated print-

25 ing and non-printing characters so positioned that when a printing character is at the opening in the lower casing, the duplicate non-printing character is at said sight opening, means whereby said frame may be actuated, a ratchet wheel

30 carried by each of said other wheels, having teeth corresponding in number with the printing characters thereon, a spring pressed detent pawl co-operating with each ratchet wheel, and co-operating means carried by said rewind reel

35 and said reciprocatory frame whereby said strips will be advanced with each upward movement of said frame.

14. A collector's stamp embodying therein a lower casing having an opening through the bottom thereof, and side bars having bearing saddles adjacent the opposite ends thereof, supply

40 and rewind reels removably mounted in said saddles, a plurality of superimposed strips of record and carbon paper passing from said supply to said

45 rewind reel with a carbon coated surface presented towards said opening, guides for said strips, an upper casing having a sight opening therethrough, closing said lower casing, movable

50 therefrom and having therein a guide bracket having vertical ways having extensions provided with bearing saddles co-operating with the saddles in said side bars, a spring carried by said upper casing and engageable with said supply reel, a reciprocatory frame, a shaft carried thereby having

55 its opposite ends mounted in said ways, and a plurality of wheels idly mounted on said shaft, and projecting through said sight opening, each having a plurality of duplicated printing and non-printing characters so positioned that when

60 a printing character is at the opening in the lower casing, the duplicate non-printing character is at said sight opening, a ratchet wheel carried by each of said other wheels having teeth

65 corresponding in number with the printing characters thereon, a spring pressed detent pawl co-operating with each ratchet wheel, means whereby said frame may be actuated, and co-operating means carried by said rewind reel and said reciprocatory frame whereby said strips will be

70 advanced with each upward movement of said frame.

GEORGE J. MATT.
